(57) **CLAIM**

The ornamental design for a vibrating massager base, as shown.

DESCRIPTION

FIG. 1 is a 3-dimensional perspective view of a vibrating massager base showing our new design;

FIG. 2 is a front elevation view thereof;

FIG. 3 is a rear elevation view thereof;

FIG. 4 is a left side view thereof;

FIG. 5 is a right side view thereof;

FIG. 6 is a bottom plan view thereof; and,

FIG. 7 is a top plan view thereof.
